United States Patent Office

Des. 182,555
Patented Apr. 15, 1958

182,555

APRON

Jack W. Vinetz, Los Angeles, Calif.

Application January 18, 1957, Serial No. 44,530

Term of patent 7 years

(Cl. D3—26)

FIG. 1

I claim:

The ornamental design for an apron, substantially as shown.
